LIDDING MACHINE

Hale Paxton, Redlands, Calif., assignor to Paxton Credit Corporation, Sanger, Calif., a corporation of California

Application September 6, 1932, Serial No. 631,790

16 Claims.

(Cl. 1—10)

My invention relates to the art of securing covers to shipping cases, and more particularly to a lidding machine for applying and securing covers to shipping crates when the latter are lined and crown packed. In the agricultural industry many fruits and vegetables are packed in suitable crates or boxes for shipment, it being customary to overfill these shipping cases so that the contents thereof extend above the top of the case to form a "crown pack". Certain produce, such as fresh lettuce, is packed in crates which are provided with oiled paper liners, the end portions of these liners hanging over the crate sides to form flaps which are folded over the top of the pack prior to the lidding of the case.

Layers of lettuce and layers of cracked ice are placed alternately in the lettuce crates, these crates being overfilled so that the crown of the pack often extends 8 to 10 inches above the top of the crate. When this type of pack is compressed by the lidding machine as the lid is being applied to the crate, the liner flaps which cover the crown of the pack are given considerable slack which results in a wrinkled, untidy appearing liner after the lid is nailed in place.

Due to the curvature of the top of a crown packed crate most of the slack in the liner flaps occurs at ends of the crate.

It is, therefore, an object of my invention to provide a lidding machine which is adapted to take up the slack condition of liner flaps above noted, particularly at the ends of the crate, so that after a lid is applied to the crate the liner flaps will be left tightly drawn over the crown of the pack.

Further objects and advantages will be made manifest in the following description taken in connection with the accompanying drawings, in which:

Fig. 1 is a fragmentary front elevational view of a preferred form of lidding machine of my invention.

Fig. 2 is a fragmentary side elevational view of the machine shown in Fig. 1 taken in the direction of the arrow 2 of Fig. 1.

Fig. 3 is a perspective view of a packed lettuce crate.

Fig. 4 is a fragmentary, front elevational view of a portion of the machine shown in Fig. 1 showing a stage in the operation thereof.

Figs. 5 and 6 are fragmentary vertical sectional views taken on the lines 5—5 and 6—6 respectively of Fig. 4.

Fig. 7 is a fragmentary front elevational view

of a modified form of lidding machine of my invention.

Fig. 8 is a fragmentary vertical sectional view taken on the line 8—8 of Fig. 7.

Fig. 9 is a fragmentary elevational view showing a stage in the operation of the machine as shown in Fig. 7, and

Fig. 10 is a fragmentary vertical sectional view taken on the line 10—10 of Fig. 9.

Referring specifically to the drawings, a lidding machine 10 comprising a preferred embodiment of my invention is shown in Figs. 1 to 6 inclusive, this machine including a frame 11, a crate elevator 12, nailing mechanism 13, end tuckers 14, and side tuckers 15.

Referring particularly to Figs. 1 and 2, the frame 11 includes a suitable base (not shown), from which extends a pair of vertical standards 20 joined at the upper ends thereof as by a cross-bar 21. Secured to and extending forwardly from upper portions of the standards 20 are brackets 22. Fixed at opposite ends thereof to the brackets 22 are front and rear horizontally aligned rods 23 and 24, respectively, as shown in Figs. 1 and 6.

The elevator 12 includes a hydraulic cylinder 25 having a piston (not shown) from which a piston rod 26 extends vertically. Slidable vertically in the frame 11 and fixed to the upper end of the piston rod 26 is a crate receiving platform 27, the latter being adapted to be raised and lowered by the cylinder 25. Operatively mounted on the platform 27 are automatic crate stops 28 as shown in Fig. 1.

The nailing mechanism 13 includes a plurality of nail chucks 32, the latter having drivers 33 slidable vertically therein as shown in Fig. 1. The drivers 33 are actuated by a suitable mechanism (not shown) at the will of the operator of the machine 10.

A detailed description of the structure and operation of the crate elevator 12 and nailing mechanism 13 will be found in my copending application for U. S. Letters Patent Serial No. 587,388, filed January 18, 1932, for Lidding machine.

The end tuckers 14 are supported at opposite sides of the machine 10 below the brackets 22 by means of depending arms 35 and links 36, the arms 35 having integral collars 37 which are fixed to opposite ends of the rods 23 and 24, as shown in Figs. 1 and 2.

The side tuckers 15 are swung from the rods 23 and 24 by apertured mounting arms 40, as shown in Figs. 1 and 5, the arms 40 being positioned on the rods 23 and 24 by suitable collars 55.

55

41. Bolted to the arms 40, adjacent the lower edges thereof, are horizontal bars 42 to which front and rear identical side tucker plates 43 are fixed. The lower edges of the plates 43 are formed, as shown in Fig. 1, to provide end portions 44 which extend downward below a central portion 45 thereof.

10 The end tuckers 14 and side tuckers 15 are adapted to be operated by a suitable mechanism 47, the latter being actuated in response to vertical movement of the platform 27 by a vertical rod 48.

15 A detailed description of the structure and operation of the end tuckers 14, side tuckers 15, and the mechanism 47 will be found in my copending application for U. S. Letters patent, Serial No. 554,212, filed July 31, 1931, for Lidding machine.

20 The machine 10 of my invention differs from the lidding machine of my copending application Serial No. 554,212 only in the formation and operation of the aforementioned side tucker plates 43.

25 The crate 29, shown in the drawings, illustrates a typical lettuce pack, this crate having an oiled paper liner 50 provided therein. The liner 50 is placed in the crate 29 prior to filling the crate, and the loose ends of the liner are allowed to hang over the ends and sides of the crate to form end flaps 51 and side flaps 52. After the lettuce and cracked ice are packed in the crate, the end flaps 51 and side flaps 52 are folded over the top of the pack with the side flaps on top, as shown in Fig. 3. Due to the curvature of the top of the lettuce pack, as aforementioned, the side flaps 52 only contact the center portion of the pack, it being noted that edges 53 of the side flaps 52 are disposed in spaced relation with the lettuce pack as shown in Fig. 1.

Operation

40 Crates, such as the crate 29, are fed onto the platform 27 of the machine 10 by a suitable delivery conveyor (not shown) and the crate is automatically positioned on the platform 27 by the stops 28, as shown in Fig. 1. A lid 55 is manually placed in the machine 10 and is supported by the end tuckers 14 as shown. The operator then depresses a foot pedal (not shown) which causes the hydraulic cylinder 25 to elevate the platform 27 and crate 29.

50 The side tuckers 15 are normally positioned as shown in Fig. 2, and when the crate 29 reaches a predetermined point during its upward travel the rod 48 actuates the mechanism 47, the latter actuating the end tuckers 14 and the side tuckers 15. Actuation of the side tuckers 15 causes these to swing inwardly about the rods 23 and 24 so that the side tucker plates 43 gather the over-filled portion of the lettuce pack inwardly from over the upper edges of the sides of the crate 29.

60 As the crate continues upward the sides of the crate slide over the plates 43, as shown in Figs. 4, 5, and 6, it being noted that the plates 43 are now disposed between the contents of the crate and the side walls thereof. As the plates 43 contact the lettuce pack, the lower edges of these plates engage the side flaps 52 of the liner 50 and tuck portions of these flaps downwardly between the walls of the crate and the contents thereof, thus drawing the flaps 52 into firm engagement with the top of the pack.

70 Due to the fact that the end portions 44 of the plates 43 extend downward below the center portions 45 of these plates, the edge portions 53 of the side flaps 52 are tucked downward a greater distance than the center portions of the flaps 52, as shown in Fig. 6, thus

drawing the flaps 52 into firm contact with the entire upper surface of the top of the contents of the crate 29. When the crate 29 arrives at its uppermost position, as shown in Fig. 4, the lid 55 is nailed to the crate in the conventional manner and the crate is lowered and discharged from the platform 27.

10 Referring particularly to Figs. 7 to 10 inclusive, I have shown therein a lidding machine 60, the latter including a pair of modified side tucker 10 plates 61, like reference numerals being used to denote like parts in the machines 10 and 60.

15 The tucker plates 61 of the machine 60, only one of which is shown, are mounted on the rods 23 and 24 in the same manner that the plates 15 43 are mounted on the machine 10. The plates 61 are formed to provide downwardly extending end portions 62 and rectangular openings 63, as shown in Fig. 7. Formed integral with, and extending upwardly from the upper edges of the 20 plates 61 are projections 64 to which bearings 65 are fixed. Secured to the plates 61 in vertical, axial alignment with the bearings 65 are bearings 66.

25 Slidable vertically in the openings 63 of the 25 plates 61 are rectangular plates 67, the surfaces of the latter being disposed in alignment with the surfaces of the plates 61. Welded or otherwise secured to the upper edges of the plates 67 are vertical rods 68, these being slidably received 30 by the bearings 65 and 66. The plates 67 are normally urged downwardly by springs 69, the latter bearing against pins 70 in the rods 68 as shown. Fixed on the outer surfaces of the plates 67 by screws 71 are angle iron bars 72, the latter 35 extending beyond the plates 67 in overlapping relation with the portions 62 of the plates 61 as shown. Provided in the plates 67 are pairs of horizontally aligned holes 73 adapted to threadedly receive the screws 71 for the purpose of adjusting the angle bars 72 vertically on the plates 67.

40 The normal position of the slidable plates 67 relative to the plates 61 is shown in Figs. 7 and 8, it being noted that the lowermost points of the 45 plates 67 and portions 62 of the plates 61 are disposed in substantial horizontal alignment. The plates 67 remain in this position during the gathering of the overflow portion of the pack in the crate 29, as shown in Fig. 8, and as the crate 50 sides slide up over the plates 61, portions of the side flaps 52 of the crate liner 50 are tucked downward between the walls and contents of the crate. As the sides of the crate continue to slide upwardly over the plates 61, the upper edges of 55 the crate sides contact the angle bars 72 of the plates 67 causing these plates to be lifted with the crate as shown in Figs. 9 and 10. As the plates 67 rise with the crate 29, the end portions 60 62 of the plates 61 continue their tucking action until the slack edge portions 53 of the flaps 52 are drawn into snug contact with the top of the contents of the crate 29.

65 After the crate 29 is lidded by the machine 60 the crate is lowered as aforescribed and the 65 plates 67 are spring-pressed downwardly to their normal position as shown in Fig. 7.

70 It is seen that I have provided a very simple side tucking means for lidding machines which will take up the slack condition of crate liners 70 so that the lining in lidded crates will be snugly drawn over the pack and thus present a neat appearance.

75 Although I have shown and described but one preferred and one modified form of my invention, 75

it is to be understood that various modifications and changes might be made in these embodiments of my invention without departing from the spirit and scope of the appended claims.

5 I claim as my invention:

1. In a machine for lidding a lined and over-filled shipping crate with portion of said liner folded over the top of the contents of said crate and with excess top portions of said liner disposed over end portions of said contents, the combination of: means for pressing a lid onto said crate so as to bow the ends of the lid downwardly against the ends of the crate permitting the middle of the lid to be bowed upwardly by said contents; and means for tucking slack occurring in said liner along the sides of said crate, as said lid is pressed onto said crate, downwardly a given distance inside the upper side slats of said crate at the middle of said slats and greater distances at the ends of said slats. 10
2. In a machine for lidding a lined and over-filled shipping crate with portions of said liner folder over the top of the contents of said crate and with excess top portions of said liner disposed over end portions of said contents, the combination of: means for pressing a lid onto said crate so as to bow the ends of the lid downwardly against the ends of the crate permitting the middle of the lid to be bowed upwardly by said contents; a pair of tuckers disposed at opposite sides of said crate; and means for shifting said tuckers inwardly over the interior of said crate and for causing relative vertical movement between said crate and said tuckers to bring said tuckers inside 15 of the upper side slats of said crate, said tuckers including central portions for tucking said liner downwardly a given distance at the middle of said crate, and end portions for tucking said liner downwardly greater distances at the ends of said 20 crate. 25
3. In a machine for lidding a lined and over-filled shipping crate with portions of said liner folded over the top of the contents of said crate and with excess top portions of said liner disposed over end portions of said contents, the combination of: means for pressing a lid onto said crate in position for securing said lid to said crate; a pair of side tucking members provided on said machine; downwardly extending tucking blades provided at opposite ends of said tucking members; supplementary tucking blades slideable vertically between said end tucking blades; and means for substantially terminating relative vertical movement of said supplementary tucking blades and said crate prior to the termination of relative 30 vertical movement of said end blades and said 35 crate. 40
4. In a machine for lidding a lined and over-filled shipping crate, the combination of: means for pressing a lid onto said crate in position for securing said lid to said crate; tucking means provided on said lidding machine, said tucking means being adapted to gather overfilled portions of said crate contents inwardly from over the upper edges of the sides of said crate; and liner tucking blades provided on said tucking means, said blades being formed at their lower edges with end portions thereof extending downwardly beyond the center portions thereof. 45
5. In a liner tucking device for a lined crate lidding machine, the combination of: a plurality of tucker blades; means disposing said blades vertically to tuck portions of a crate liner downwardly between the walls and contents of said crate; and means for limiting the degree of tucking action of certain of said blades relative to 50 the upper edges of said walls of said crate. 55
6. In a machine for lidding a lined and over-filled shipping crate with portions of said liner folded over the top of the contents of said crate and with excess top portions of said liner disposed over end portions of said contents, the combination of: means for tucking said excess portions of said liner downward between the side walls and contents of said crate; supplementary tucking means slidably mounted on said first mentioned tucking means; and means provided on 10 said supplementary tucking means for limiting relative vertical movement of said supplementary tucking means and said crate. 60
7. In a machine for lidding a lined and over-filled shipping crate with portions of said liner folded over the top of the contents of said crate and with excess top portions of said liner disposed over end portions of said contents, the combination of: means for tucking said excess portions of said liner downward between the side walls and 15 contents of said crate; supplementary tucking means slidably mounted on said first mentioned tucking means; and stop means provided on said supplementary tucking means, said stop means being adapted to contact upper edges of said side 20 walls of said crate to as to limit the tucking action of said supplementary tucking means. 25
8. In a machine for lidding a lined and over-filled shipping crate, the combination of: means for pressing a lid onto said crate in position for 30 securing said lid to said crate; a pair of side tucking members provided on said machine; downwardly extending tucking blades provided at opposite ends of said tucking members; supplementary tucking blades slideable vertically between said end tucking blades; and means for substantially terminating relative vertical movement of said supplementary tucking blades and said 35 crate prior to the termination of relative vertical movement of said end blades and said 40 crate. 45
9. In a machine for lidding a lined and over-filled shipping crate, the combination of: means for pressing a lid onto said crate in position for securing said lid to said crate; a pair of side tucking members provided on said machine; downwardly extending tucking blades provided at opposite ends of said tucking members; supplementary tucking blades slideable vertically between said end tucking blades; means for terminating relative vertical movement of said supplementary tucking blades and said 50 crate prior to the termination of relative vertical movement of said end blades and said 55 crate; and means for varying the point of said termination of relative vertical movement of said supplementary tucking blades and said crate. 60
10. In a machine for lidding a lined and over-filled shipping crate, the combination of: means for pressing a lid onto said crate in position for 60 securing said lid to said crate; liner tucking means; and means for causing relative vertical movement between said crate and said tucking means to extend the latter into said crate to tuck a portion of said liner downwardly between the 65 walls and contents of said crate, said tucking means then yielding to said last mentioned means. 70
11. In a machine for lidding a lined and over-filled shipping crate, the combination of: means for pressing a lid onto said crate in position for 70 securing said lid to said crate; liner tucking means adapted to tuck portions of said liner downwardly between the walls and contents of said crate, said tucking means being mounted so as to be yieldable vertically; and stop means 75

provided on said tucking means, said stop means being adapted to contact said crate so as to limit the relative vertical movement of said tucking means and said crate.

5 12. In a machine for lidding a lined and over-filled shipping crate, the combination of: means for pressing a lid onto said crate in position for securing said lid to said crate; liner tucking means adapted to tuck portions of said liner 10 downwardly between the walls and contents of said crate, said tucking means being mounted so as to be yieldable vertically; and means for selectively limiting the degree of tucking action of said tucking means relative to the upper edges of said crate.

15 13. In a machine for lidding a lined and over-filled shipping crate, the combination of: means for pressing a lid onto said crate in position for securing said lid to said crate; liner tucking 20 means adapted to tuck portions of said liner downwardly between the walls and contents of said crate, said tucking means being mounted so as to be yieldable vertically; and stop means provided on said tucking means, said stop means being adjustable vertically and adapted to contact said crate so as to limit the relative vertical movement of said tucking means and said crate.

25 14. In a machine for lidding a lined and over-filled shipping crate with portions of said liner folded over the top of the contents of said crate and with excess top portions of said liner disposed over end portions of said contents, the 30 combination of: means for pressing a lid onto

said crate in position for securing said lid to said crate; a side tucking member associated with said lidding machine, end portions of said tucking member extending downwardly a greater distance than the center portion thereof; and means for thrusting said tucking member downwardly between a vertical wall of said crate and the contents thereof so as to tuck said liner between said wall and said contents.

5

15 15. In a machine for lidding a lined and over-filled shipping crate with portions of said liner folded over the top of the contents of said crate and with excess top portions of said liner disposed over end portions of said contents, the combination of: tucking means extending downward between a side wall and the contents of said crate, said tucking means carrying said liner down between said wall and said contents; supplementary tucking means slidably mounted on said first mentioned tucking means and 20 means provided on said supplementary tucking means for limiting relative vertical movement of said supplementary tucking means and said crate.

15

16. In a machine for lidding a lined and over-filled shipping crate, the combination of: means 25 for pressing a lid onto said crate in position for securing said lid to said crate; a vertically yieldable tucker; means for extending said tucker between a side wall and the contents of said crate; and means for selectively limiting the degree of 30 tucking action of said tucker relative to the upper edge of said side wall.

HALE PAXTON.
